UNITED STATES PATENT OFFICE.

T. MUSGRAVE, OF LEEDS, MASSACHUSETTS, ASSIGNOR TO ANNA L. MUSGRAVE, OF NORTHAMPTON, MASSACHUSETTS.

MACHINE FOR BURRING WOOL.

Specification of Letters Patent No. 19,816, dated March 30, 1858.

To all whom it may concern:

Be it known that I, THOMAS MUSGRAVE, of Leeds, in Hampshire county, in the State of Massachusetts, have invented a new and useful Improvement in Machines for Burring Wool; and I do hereby declare that the following is a full, clear, and exact description thereof, reference being had to the accompanying drawings, making part of this specification, in which—

Figure 1, is a plan; Fig. 2, a side elevation; and Fig. 3, a longitudinal vertical section.

The same letters indicate like parts in all the figures of the said drawing.

The leading object of my invention is to cleanse wool of what is known as the mestizo bur, although it will more effectually, and with less labor and less injury to the fiber than any other known means, cleanse wool which has other burs or other solid impurities. The mestizo bur is of peculiar structure. If opened carefully it will be found to be composed of long fibers of a hard woody substance, with short and hard fibers projecting like barbs on the edges of the long fibers which they in part connect. And these long fibers with their barbs are rolled up in several convolutions in a snail like form embracing some of the fibers of wool which are aggregated about the bur, and which finally envelop it much in the manner of a pod of cotton fibers surrounding the seed. The mode generally practiced of cleansing such wool is to subject it to the operation of what is known as a picker by which the fibers are torn from the burs, and then transfer it to what is known as a burring machine—and for the reason that the burring machine heretofore known could not alone effectually cleanse such wool; but serious difficulties have been, and are, experienced in the mode of treatment above referred to. The picker in tearing the fibers of wool from the mestizo bur not only injures the fiber seriously but frequently unwinds the burs, the barbs of which remain attached to the fibers; and as the fibers of wool are drawn out the long fibers of the bur, which lie along parallel with it, fail to be knocked off when passing through the burring machine. And such portions of the burs as remain attached to the fibers when delivered from the burring machine are not removed when passing

through the card and other after processes in the manufacture, and when woven into the cloth can then be felt projecting from the surface of the cloth which is thereby depreciated in value. In addition to all this the action of the picker is known to be injurious to the fibers of wool generally, the fact having long been noticed that the violent action on the fibers injures their felting property.

My said invention relates to an improvement on that class of burring machines in which the cylinder is composed of a series of circular disks or equivalent construction with interposed washers having sufficient space between the several disks for the reception of the fibers of wool, but not sufficient to receive the burs, the peripheries of the said disks being formed with gullets cut therein at given distances apart to catch and draw in the fibers of wool, rotating beaters being used in connection therewith to knock off the burs. And in view of the result to be accomplished my said invention consists in combining with such burring machine another like, and more rapidly rotating burring cylinder, by means of an interposed rotating stripper so located and rotated as to draw out the sliver, as it may be termed, in taking the fibers of wool from the first burring cylinder and transferring them to the second burring cylinder by which latter operation they are still farther drawn out and then subjected to a second and final burring operation to cleanse the fibers of all foreign substances not removed by the first.

In the accompanying drawings *a* represents the frame which may be of any suitable construction, and *b* a burring cylinder such as have been extensively used for some years past by woolen manufacturers, and composed of a series of circular disks placed on a shaft with their washers interposed between the several disks—suitable gullets being cut into the periphery of the several disks.

The wool to be burred is placed on the usual feeding apron which passes around the rollers *c c*, and thence the wool is taken by a pair of feed rollers *d d* and by them presented to the burring cylinder *b* by which it is taken, the fibers drawn into the gullets and between the several disks, while the burs project beyond the periphery of the

cylinder where, by the operation of the rotating beaters *e*, the burs are gradually rolled out of the fibers of wool and knocked off, the said beaters being rotated by suitable gearing in the directions indicated by the several arrows.

Back of the burring cylinder *b* is placed a rotating stripper *f* clothed with card teeth in the usual manner of a card stripper. 10 The periphery of this stripper moves faster than that of the burring cylinder and draws the fibers of wool out of the burring cylinder, and in drawing them out and stretching them brings the small impurities, such as the 15 barbed fiber of the mestizo bur, which may have been opened, and then transfers them to a second burring cylinder *g*, constructed like the one *b*, and which rotates at a higher velocity than the first, and by which the 20 fibers of wool are taken, drawn into the gullets and between the several disks, but leaving outside of the periphery such impurities as were concealed in the fiber or in the gullets and between the several disks 25 of the first burring cylinder. The fibers thus taken by the burring cylinder *g* are carried up to the action of rotating beaters *h*, similar to those before described, which knock off the remaining foreign substances, 30 leaving the fibers in a thoroughly cleansed state, and then they are drawn out of the burring cylinder by a rotating wire brush or other stripper *i*. In this way I am enabled not only to dispense entirely with the use of a 35 picker, but the fibers of wool are more thoroughly stripped of all burs, or parts of burs and other solid impurities, than they can be by any other known means.

The same result could not be accomplished 40 by simply using two burring machines in succession to operate on the wool, because in taking the fibers delivered from the first machine and placing them on the feed apron of the second machine the fibers would lose

that distended condition in which they are 45 when leaving the burring cylinder—they could not be placed on the second feed apron in the same regular order in which they left the first cylinder, and in passing between the feed rollers by which they would be 50 presented to the burring cylinder of the second machine, small particles of the mestizo bur, and of other hard substance, would become mashed down and buried between the several fibers of wool to such an extent 55 as to pass entirely out of the reach of the beaters. But by the drawing operation which takes place on the fibers in my improved machine in drawing them from the burring cylinder and transferring them to 60 the second burring cylinder the small particles above referred to are loosened from the fibers and brought to the surface so as to project from the periphery of the second burring cylinder to be removed by the beaters. And besides it will be seen that by the combination above described the fibers are more readily and with less labor transferred from the first burring cylinder to the 65 second, than they could from one burring 70 machine to another.

I do not claim the construction of the burring cylinder, or strippers, or beater, nor the combination of beaters or strippers with a burring cylinder. But

75

What I do claim as my invention and desire to secure by Letters Patent is—

The combination of the second burring cylinder and its beaters, substantially as herein described, with the first burring cylinder and its beaters, substantially as described, by means of an interposed stripper, or an equivalent therefor, as described.

THOMAS MUSGRAVE.
